UNITED STATES PATENT OFFICE.

JOHN T. DRUFVA, OF LONGMEADOW, MASSACHUSETTS, ASSIGNOR TO HENRY HYMAN & CO., INC., OF NEW YORK, N. Y., A CORPORATION OF NEW YORK.

PORTABLE ELECTRIC LIGHT.

1,272,781.

Specification of Letters Patent. Patented July 16, 1918.

Application filed April 4, 1918. Serial No. 226,582.

To all whom it may concern:

Be it known that I, JOHN T. DRUFVA, a citizen of the United States, and a resident of Longmeadow, in the county of Hampden 5 and State of Massachusetts, have invented certain new and useful Improvements in Portable Electric Lights, of which the following is a specification.

The invention pertains more particularly 10 to the character of electric flash lights to be held in the hand and lighted, as occasion may require, by the manual movement of a slide applied upon the exterior casing of the device.

15 My present invention resides more particularly in a novel arrangement and construction of parts, including a slide for completing the circuit between the lamp and battery and also a push-button or the like 20 which may be utilized independently of the slide for completing the circuit and flashing the light, the whole being arranged to obviate the accidental circuiting of the lamp by contact with metal articles, such as might 25 arise when a flash light, otherwise constructed, is placed in a box of tools.

The flash light of my invention comprises an exterior casing, a plural cell battery therein, a thumb piece or slide on the side 30 of the casing, a spring blade connected with said slide and located at the inner side of the casing for completing the circuit between the lamp and battery, a push button exposed through a hole in the side of the casing 35 and arranged to engage said blade and permit the same to be pushed inwardly independent of the slide for completing the circuit between the lamp and battery, a metal sleeve applied upon the upper end of 40 the casing and holding the lens and binding the same against the reflector, a lamp bulb of customary type held by the reflector and engaging the positive pole of the battery, and a novel support within the outer end of 45 the casing to receive the sleeve of the reflector and comprising a ring to set within the casing, an insulating disk held by said ring and serving to insulate the reflector from adjacent metal parts of the casing, a 50 metal plate at the bottom of said insulating disk in electrical connection with the sleeve of the reflector and affording a surface to be

engaged by the aforesaid blade when slid against the same by the manual actuation of said slide, and a depending annular flange 55 connected with said bottom plate and affording a surface against which by means of the aforesaid push button the upper portion of the blade connected with the slide may be moved to complete the circuit between 60 the lamp and battery. The coöperation of the push button and blade permits the lamp to be utilized for throwing flashes, such as might be required for signaling, while the same blade when employed in connection 65 with the slide may be utilized for creating a more or less permanent or constant lighting of the lamp.

The present invention pertains to further improvements on the character of flash light 70 made the subject of my application for Letters Patent No. 208,346, filed December 22, 1917, the features added to the present application and not disclosed in the aforesaid pending application relating more particularly 75 to the depending annular flange on the reflector support and the push button arranged to engage the same spring blade that is utilized in connection with the exterior thumb piece or slide for completing the circuit through the lamp and battery.

The invention will be fully understood from the detailed description hereinafter presented, reference being had to the accompanying drawings, in which:

85 Figure 1 is a central longitudinal section, with the wrapping on the battery partly broken away, of a portable flash light embodying the invention, the casing of the flash light being shown in this instance as a 90 metal tubing;

Fig. 2 is a central vertical section through the parts of the reflector support, the insulating disk and its immediate features being shown as separated from the encompassing ring and ready to be dropped thereinto, and

Fig. 3 is a bottom view of the reflector support and its several coöperating features.

In the drawings, 10 designates a tubular 100 metal casing, 11 a plural cell battery therein, 12 a wrapping of insulating material on said battery, 13 a screw-cap of customary construction closing the lower end of said eas-

ing, 14 a conducting spring compressed between the negative pole of the battery and the inner surface of said cap, 15 a sleeve screwed upon the outer end of said casing, 5 16 a customary lens held by said sleeve, 17 a reflector within the outer end of the casing 10 and out of electrical contact therewith, and 18 an electric bulb of known character having its terminal sleeve 19 screwed into 10 the usual threaded sleeve 20 at the inner end of said reflector, the other terminal 21 of the lamp being held in engagement with the positive pole 22 of the battery by means of the spring 14. Near the outer end of the 15 casing 10 said casing is enlarged laterally, whereby about in line with the lower portion of the reflector 17, an annular shoulder 23 is created, and upon this shoulder is seated a metal ring 24 comprising an upper 20 annular portion 25 which engages said shoulder, a lower annular portion 26 which projects downwardly into the upper portion of the casing 10 below said shoulder, and a horizontal flange 27 which extends inwardly 25 from the lower edges of said annular portion 26.

A disk 28 of insulating material and carrying a bottom plate or disk 29 of conducting material and having a depending 30 annular flange 30, is seated within the ring 24 and therewith forms a support for the reflector 17. The disk 28 and disk or plate 29 are secured together by an eyelet 31 down into which the sleeve 20 of the reflector projects, and the said sleeve and eyelet are in electrical contact. The metal disk or plate 29 is smaller than the insulating disk 28, as shown, and when the disk 28 with the disk or plate 29 is seated within the ring 35 40 45 50 55 60 65 70 75 80 85 90 95 100 105 110 115 120 125 130 flange 30, and being of insulating material, the disk 29 normally remains out of electrical connection with the ring 24 and also with the exterior casing 10. In assembling the parts the disk 28 carrying the disk 29, with its annular flange 30, is seated within the ring 24 and therewith introduced through the upper end of the casing 10, the said ring becoming seated on the shoulder 23, as shown. The reflector and lamp may then be applied to position, and thereafter the lens is secured against the upper edge of the reflector by means of the sleeve 15. The sleeve 15 serves to hold the lens 16 against the reflector and also to keep the reflector in constant electrical connection with the eyelet 30 of the reflector support.

Upon one side of the casing 10 is provided a thumb piece or slide 32 which is secured to an inner conducting strip or spring blade 33 by means of eyelets or the like 34, which

enter slots formed in the casing 10 so that the slide 32 and strip or blade 33 may have sliding movement imparted to them by the user of the flash light. In Fig. 1 I illustrate the slide 32 and strip or blade 33 in 70 their outer position completing the circuit through the lamp and battery, the upper or outer end of the strip or blade 33 being bent inwardly, as at 35, so that when said strip is moved to its outer position the said bent 75 end will pass into electrical contact with the disk 29 at that portion thereof which projects outwardly in a lateral direction beyond the outer surfaces of the flange 30. The strip or blade 33 is of spring metal and when 80 moved to its outer position, the bent end 35 thereof may be pressed with spring effect against the outer edges of the disk 29 and thereby assure positive electrical connection between said strip and said disk. When the 85 slide 32 is moved downwardly from its position shown in Fig. 1 it will carry the strip or blade 33 downwardly and break the connection between the upper end of the strip and the lower surface of the disk 29, thus 90 breaking the circuit and extinguishing the light.

Outwardly beyond the slide 32 the casing 10 is apertured to receive a push button 36 which is freely movable in said aperture and 95 is flanged at its inner edge to engage the inner surface of the casing 10 and thus prevent its escape from said casing. The inner flanged edge of the push button 36 engages the outer flat surface of the strip or 100 blade 33 and when the slide 32 is in its lower position may be utilized to press said strip or blade 33 against the depending flange 30 of the disk 29 for thereby completing the circuit and lighting the lamp. When the 105 slide 32 is moved to its lower position, the outer end of the strip or blade 33 becomes free from the disk 29, but stands in line with and free of the lower portion of the flange 30. At this time should it be desired 110 to flash the lamp instead of having a somewhat permanent light, the user of the flash light may alternately press the button 36 inwardly and allow the spring action of the strip or blade to move the same outwardly 115 as frequently as may be desired, each inward movement of the push button 36 moving the upper end of the strip or blade 33 against the flange 30 and completing the circuit. It is obvious that if desired the operator may 120 use the push button 36 in obtaining a more or less permanent light, although ordinarily when such light is desired, the slide 32 will be made use of.

It will be observed that with very slight 125 additional expense I equip the electric light with means for obtaining a more or less permanent light and also for flashing the light, the same conducting strip or blade being utilized for both purposes and being 130

properly held by the thumb piece or slide so as to permit both actions.

What I claim as my invention and desire to secure by Letters-Patent, is:

- 5 1. In a flash light having a casing, reflector, lens, lamp bulb and battery, said reflector having a portion receiving the lamp socket, in combination, an insulating disk within the forward end of the casing, a 10 metal disk at the lower face thereof, a depending flange electrically connected with said metal disk, and means for making and breaking the circuit through the lamp and battery comprising a slide on said casing, a 15 spring blade within the casing connected with said slide and movable thereby to complete the circuit through said metal disk, and a push button mounted in said casing and engaging said spring blade and adapted 20 on being pressed inwardly to move said blade against the aforesaid depending flange, the normal position of the upper end of said blade being opposite to said flange and the lower terminal of the lamp being in engagement 25 with the positive pole of the battery, while said metal disk is in electrical connection with the other terminal of the lamp.

2. In a flash light having a casing, reflector, lens, lamp bulb and battery, in combination, an insulating disk within the forward portion of said casing, a metal plate on the lower side of said disk, a depending metal flange at the lower side of said plate and in electrical connection therewith, a 35 metal eyelet connecting said disk and plate and receiving the lower tubular portion of said reflector, and means for making and breaking the circuit through the lamp and battery comprising a slide on said casing, a 40 spring blade within the casing connected with said slide and movable thereby to complete the circuit through said metal plate, and a push button mounted in said casing and engaging said spring blade and adapted 45 on being pressed inwardly to move said blade against the aforesaid depending flange, one terminal of the lamp being in engagement with the positive pole of the battery and the other terminal of the lamp being in electrical connection 50 with said metal plate and the upper end of said blade being normally opposite to said flange.

3. In a flash light having a casing, reflector, lens, lamp bulb and battery, in combination, an insulating disk within the forward end of said casing, a metal plate held by said disk, a depending metal flange electrically connected with said plate, and means for making and breaking the circuit through the lamp and battery, comprising a slide on 55 said casing, a spring blade within the casing connected with said slide and movable thereby to complete the circuit through said metal plate, and a push button mounted in said casing and engaging said spring blade and adapted 60 on being pressed inwardly to move said blade against the aforesaid depending flange, one terminal of the lamp being in engagement with the positive pole of the battery and the other terminal of the lamp being in electrical connection with said metal plate and the upper end of said blade being normally opposite to said flange.

move said blade against the aforesaid depending flange, one terminal of the lamp being in engagement with the positive pole of the battery, and the other terminal of the lamp being in electrical connection with 70 said metal plate.

4. In a flash light having a casing, reflector, lens, lamp bulb and battery, in combination, an insulating disk within the forward portion of said casing, and a metal 75 plate held thereby and having a depending metal flange set inwardly from the outer edges thereof, and means for making and breaking the circuit through the lamp and battery comprising a slide on said casing, a 80 spring blade within the casing connected with said slide and movable thereby to complete the circuit through said metal plate, and a push button mounted in said casing and engaging said spring blade and adapted 85 on being pressed inwardly to move said blade against the aforesaid depending flange, one terminal of the lamp being in engagement with the positive pole of the battery and the other terminal of the lamp being in 90 electrical connection with said metal plate.

5. In a flash light having a casing, reflector, lens, lamp and battery, in combination, an insulating disk within the forward portion of said casing, and a metal plate held 95 thereby and having a depending metal flange set inwardly from the outer edges thereof and means for making and breaking the circuit through the lamp and battery comprising a slide on said casing, a spring 100 blade within the casing connected with said slide and movable thereby to complete the circuit through said metal plate, and a push button mounted in said casing and engaging said spring blade and adapted on being 105 pressed inwardly to move said blade against the aforesaid depending flange, one terminal of the lamp being in engagement with the positive pole of the battery and the other terminal of the lamp being in electrical connection with said metal plate and the upper 110 end of said blade being normally opposite to said flange.

6. In a flash light having a metal casing, metal reflector, lens, lamp bulb and battery, in combination, a metal plate supported within the forward portion of said casing and in electrical connection with the reflector and having a depending flange, means normally insulating said metal plate from said casing, and means for making and breaking the circuit through the lamp and battery comprising a slide on said casing, a spring 115 blade within the casing connected with said slide and movable thereby to complete the circuit through said metal plate, and a push button mounted in said casing and engaging said spring blade and adapted on being 120 pressed inwardly to move said blade against the aforesaid depending flange, one terminal of the lamp being in engagement with the positive pole of the battery and the other terminal of the lamp being in electrical connection with said metal plate and the upper 125 end of said blade being normally opposite to said flange, one terminal of the lamp being in engagement with the positive pole of the battery and the other terminal of the lamp being in electrical connection with said metal plate and the upper end of said blade being normally opposite to said flange, one terminal of the lamp being in engagement with the positive pole of the battery and the other terminal of the lamp being in electrical connection with 130 said metal plate.

of the lamp being in engagement with the positive pole of the battery and the other terminal of the lamp being in electrical connection with said metal plate, and the upper end of said blade being normally positioned opposite to said flange, and said reflector at its upper edge being spaced from the surrounding metal parts of the flash light.

Signed at Springfield, in the county of Hampden, and State of Massachusetts, this 10
2nd day of April, A. D. 1918.

JOHN T. DRUFVA.
